DESIGN.

H. H. PATTEE.

BADGE.

APPLICATION FILED MAY 27, 1916.

51,267.

Patented Sept. 11, 1917.

Inventor

Herbert H. Pattee,

By his Attorney

James P. Duhamel,

UNITED STATES PATENT OFFICE.

HERBERT H. PATTEE, OF NEW YORK, N. Y.

DESIGN FOR A BADGE.

51,267.

Specification for Design. Patented Sept. 11, 1917.

Application filed May 27, 1916. Serial No. 100,402. Term of patent 7 years.

To all whom it may concern:

Be it known that I, HERBERT H. PATTEE, a citizen of the United States, and resident of New York, in the county of New York and State of New York, have invented a certain new, original, and ornamental Design for a Badge, of which the following is a specification, reference being had to the accompanying drawing, forming a part of this application, and which represents a front elevation of the device.

What I claim is:

The ornamental design for a badge as shown.

Signed at New York, in the county of New York, and State of New York this 19th day of May A. D. 1916.

HERBERT H. PATTEE.
